ADSORPTIVE FRACTIONATION PROCESS

Raymond N. Fleck, Whittier, and Carlyle G. Wight, Fullerton, Calif., assignors to Union Oil Company of California, Los Angeles, Calif., a corporation of California

Application May 3, 1957, Serial No. 656,824

18 Claims. (Cl. 183—114.2)

This invention relates to the fractionation of fluid mixtures, whether gaseous or liquid, and relates in particular to the fractionation of hydrocarbon mixtures, such as gasoline for example, to separate components or impurities therefrom.

Gasoline improvement to raise the antiknock rating is required to provide an adequate fuel for modern, high compression, internal combustion, reciprocating piston engines. Gasoline in general comprises many individual components, including hydrocarbons having between about 4 and about 12 carbon atoms per molecule. In this range are found many straight and branched chain paraffin hydrocarbons, straight and branched chain olefin hydrocarbons in cracked gasolines, as well as many naphthene and aromatic hydrocarbons. The complexity of gasoline stocks is appreciated by the fact that there are some 660 possible paraffin isomers and over 3800 possible olefin hydrocarbon isomers in this range of from 4 to 12 carbon atoms per molecule. In addition, there are a great many naphthene and aromatic hydrocarbons. Each component has its own tendency to knock in internal combustion engines and its molecular character strongly governs this tendency. In general, the straight chain or normal paraffin hydrocarbons have the greatest tendency to knock and therefore have the lowest antiknock rating. The naphthene hydrocarbons have a slightly higher antiknock rating, followed by the normal olefins, the iso-olefins, the iso-paraffins, and the aromatic hydrocarbons have the highest antiknock rating.

The gasoline is a mixture therefore that has an antiknock rating which is a function of its composition. Straight-run gasoline generally has a low rating due to its relatively high normal paraffin content and relatively low iso-paraffin and aromatic content. Cracked gasolines on the other hand have higher antiknock ratings due to the presence of normal and iso-olefin hydrocarbons. Distillation alone is not especially effective in removing only the low antiknock rating components since the rating is essentially determined by molecular structure rather than boiling point.

In the past, effective antiknock rating increase has been accomplished by the addition of materials to the gasoline such as antiknock agents like tetraethyllead, the addition of hydrocarbon components of very high knock ratings such as the alkylate of iso-butane and iso-butylene, or aromatic hydrocarbons, and the like. Antiknock rating increase is also obtainable by high temperature treatment such as thermal or catalytic cracking, catalytic or thermal dehydroaromatization or reforming, and the like. Such treatment effectively converts some of the low antiknock rating components into components having higher knock ratings.

2

The addition of antiknock agents or of hydrocarbons of usually high antiknock rating is expensive since usually they must be purchased or synthesized for such use. Even the high temperature treatments to raise the knock rating are only partly effective since the product from these processes still contains appreciable quantities of low antiknock rating materials. For example, a desulfurized naphtha having a knock rating of 51 (F-1 clear) is reformed to effect dehydrogenation of naphthenes and dehydrocyclization of normal paraffins to form aromatic hydrocarbons over a platinum catalyst to produce product having a knock rating of 96 (F-1, clear). Although this knock rating is satisfactory in some cases, the product still contains about 13% by volume of normal paraffins whose antiknock ratings are of the order of 20 or less.

Certain aromatic hydrocarbon mixtures such as coal tar fractions and the effluent produced by catalytic dehydrogenation or aromatization of certain light petroleum fractions contain rather high percentages of aromatic hydrocarbons. These streams are desirable in the blending of high antiknock rating gasolines as indicated above, in the production of aromatic solvents, in the preparation of pure aromatic hydrocarbons for chemical synthesis, and in other uses. The presence of non-aromatic hydrocarbons such as paraffins and the like in gasoline blending stocks is undesirable. The separation of such hydrocarbons is conventionally performed by superfractionation, low temperature crystallization, and the like. These processes are expensive because of their unusual and frequently extreme operating conditions. The present invention is especially applicable to these separations, as well as to others.

Therefore the present invention is directed to an improved process adapted to the fractionation of complex fluid mixtures in the presence of a solid adsorbent of a particular type, and in which the process is improved by the sequential contact of the rich adsorbent with an exchange component in two stages including a subsequent contact of the lean adsorbent with the effluent produced in the first exchange component contact stage.

It is accordingly the primary object of this invention to provide an improved adsorptive fractionation process for the separation of complex mixtures to produce at least one fraction consisting essentially of molecules of a particular species.

It is a further object of this invention to increase substantially the contacting efficiency and product purity in such adsorptive fractionation processes by employing plural stage displacement exchange of the adsorbed materials with a recirculated displacement medium under essentially isothermal conditions to produce an intercut for recirculation in the process.

It is a more specific object of this invention to reduce to essentially zero the contamination of product fluids in an adsorptive fractionation process in which the adsorbed fraction is desorbed under isothermal conditions.

It is also an object of this invention to provide an improved process step for contacting adsorbent solids with a fluid mixture whereby progressively increasing fluid velocities are maintained throughout the adsorbent contacting zone.

Other objects and advantages of the present invention will become apparent to those skilled in the art as the description and illustration thereof proceed.

Briefly the present invention comprises an improved

adsorptive fractionation process in which a complex feed mixture is contacted in a first stage with the adsorbent whereby the more readily adsorbable constituents are adsorbed forming a rich adsorbent leaving the less readily adsorbable materials as a substantially unadsorbed lean effluent. This lean effluent consists of the unadsorbable constituents of the feed stream together with substantial quantities of a displacement exchange fluid displaced from the adsorbent when the adsorbable feed fraction was adsorbed. It is distilled or otherwise fractionated to separate these components, the displacement exchange stream being recirculated in the process and the nonadsorbable portion of the feed being produced as a process product.

The recovery of the adsorbed fraction from the rich adsorbent according to this invention is characterized by the fact that it is substantially isothermal relative to the feed contacting step and that elevated temperatures are not required in order to strip or desorb the adsorbed phase from the adsorbent. There are no adsorbent heating or cooling steps as in the conventional adsorptive fractionation processes. Rather, the contacting temperatures are all about equal, differing slightly and only incidentally from each other, due to some internal thermal effects and to differences in inlet temperatures of the adsorbent and the fluid entering the contacting zones. The rich adsorbent is next contacted with a relatively minor fraction of the total displacement exchange stream in a second stage of the process to produce an intercut consisting of a mixture of the displacement exchange fluid and the initially displaced fraction of fluids present on the adsorbent. These fluids include a major proportion of components of the feed which normally are nonadsorbable and a minor proportion of materials which are adsorbable. This intercut is separated and employed in a subsequent step to contact the adsorbent.

The thus treated adsorbent is next contacted in the third stage with a major proportion of the displacement exchange stream under substantially isothermal conditions to displace the adsorbed materials from the adsorbent. The stream thus produced consists of the adsorbable fraction of the feed together with the displacement exchange fluid. This mixture is separately distilled or otherwise fractionated to recover the displacement exchange stream for recirculation in the process leaving the adsorbed feed fraction as a process product.

The adsorbent at this stage is now saturated with the displacement exchange stream. It is then contacted in the fourth stage of the process with the intercut produced in the first displacement exchange stage. The relatively small quantity of adsorbable materials in the intercut is retained by the adsorbent displacing some of the exchange component therefrom. The displaced exchange component together with the nonadsorbable feed constituents in the intercut pass through substantially unaffected. The composition of this stream is generally very similar to that produced during the first stage contact and therefore these two streams are combined. In other words, the effluent from the intercut or fourth stage contact is combined with the effluent from the feed or first stage contact and is subsequently treated with it in the manner referred to above.

The condition of the adsorbent following the fourth stage is one in which the adsorbent is essentially saturated with displacement exchange fluid but also contains a small proportion of adsorbable constituents derived from the feed and which have accumulated on the adsorbent during the fourth or intercut contacting stage. The process is then repeated starting with the first or feed contact stage and continued indefinitely.

Because of the utilization of two-stage contacting with the displacement exchange stream and the separate treatment of the intercut thus produced, the quality of the products produced is improved substantially, the degree of contamination of each of the product streams by com-

ponents desired in the other stream is decreased substantially to zero.

In one specific application of the present invention, petroleum or other naphthas boiling in the gasoline boiling range are very effectively treated to remove normal paraffin hydrocarbons of low antiknock rating selectively from the other types of hydrocarbons to produce a non-adsorbed high antiknock rating gasoline stream containing the naphthene, iso-paraffin, and aromatic hydrocarbons.

In another application of this invention, highly aromatic hydrocarbon mixtures, such as those produced in catalytic reforming of naphthenic gasoline streams or those produced in the distillation of coal, may be fractionated to remove selectively the aromatic hydrocarbons from any normal paraffins, naphthenes, and iso-paraffins.

The present type of adsorption on the particular adsorbents referred to has been found to progress at a rate which is of first order of magnitude. In other words, the rate of adsorption of the adsorbable constituents is proportional to the concentration of the adsorbable constituents in the fluid being contacted. Mathematically, this rate of adsorption is expressed as

$$25 \quad \frac{dc}{dt} = -K(c)$$

wherein c is the concentration of the adsorbable material, t is time, and K is a proportionality constant depending upon the system. In order to achieve extensive degrees 30 of adsorptive fractionation in the process, the concentration of the adsorbable component in the fluid must approach zero. According to the above relationship the rate of adsorption therefore also approaches zero so that the time necessary to achieve the desired concentration 35 may become quite long. Accordingly, in one modification of the process of this invention, progressively increasing fluid velocities are employed in the various contacting zones whereby the mass transfer coefficients are substantially increased.

40 The process and apparatus of the present invention will be more readily understood by reference to the accompanying drawings in which:

Figure 1 is a schematic flow diagram of the process of this invention using a plurality of four static beds of 45 adsorbent to produce continuously two process products of different molecular species,

Figure 2 is a schematic flow diagram of essentially the same process using a continuously moving bed of granular adsorbent, and

50 Figures 3 and 4 are simplified elevation views of contacting vessels adapted to the increasing fluid velocity in the static bed and moving bed modifications respectively.

Referring now more particularly to Figure 1, the essential 55 apparatus of the invention includes first, second, third, and fourth contacting stages or zones 10, 12, 14, and 16, and rich effluent and lean effluent distillation columns or zones 18 and 20 in which the displacement exchange recycle stream is recovered from the adsorbable 60 and the nonadsorbable feed constituents respectively.

The fluid flow through each of the contacting zones is cyclic as controlled by the four inlet control valves 22, 24, 26, and 28 and the four outlet control valves 30, 32, 34, and 36 respectively. Cycle timer operator 38 controls the positions of each of the eight inlet and outlet control valves so that the fluid flow through each contacting zone progresses through the series of four contacting 65 periods in the correct staggered sequence outlined above.

In Figure 1 the first, second, third, and fourth contacting zones 10, 12, 14, and 16 are shown in the first, second, third, and fourth contacting stages referred to previously. In contacting zone 10 the adsorbent is being contacted with the feed mixture and is producing the unadsorbable lean effluent, in zone 12 it is being contacted with the first or minor portion of the displacement

exchange stream to produce the intercut, in zone 14 it is being contacted with the larger proportion of the displacement exchange stream to produce the adsorbable components as the rich effluent, and in zone 16 it is being contacted with the intercut.

For purposes of illustration it is assumed that the feed stream in the present case comprises a catalytically reformed aromatic gasoline having the following properties:

Table 1

Boiling range	C ₆ — 400° F.
Gravity, °API	49.8
Aromatic hydrocarbons, volume percent	44.4
Normal paraffin hydrocarbons, volume percent	12.9
Knock rating, F-1 + 3 ml. TEL	97.0

The granular solid adsorbent comprises a specific zeolitic metallo alumino silicate adsorbent having pore diameters of approximately 5 Å. and having a chemical composition discussed in more detail below. This particular adsorbent exhibits preferential adsorptive forces for the normal paraffin hydrocarbons while exhibiting substantially no preferential adsorption for the other species of hydrocarbons.

The feed gasoline is introduced in the vapor phase at a temperature of about 440° F. through line 40 at a rate controlled by valve 42 into feed manifold 44. This material is directed through line 46 by inlet valve 22 into first adsorption zone 10 in which the normal paraffin hydrocarbons of the feed are preferentially adsorbed thereby displacing the adsorbed normal pentane, which in this case is lighter than any feed component and is the displacement exchange stream recycled in the process. The non-normal paraffin hydrocarbons and the displaced normal pentane flow through outlet 48 and outlet valve 30 into raffinate manifold 50. Raffinate continues through line 52 into lean effluent distillation column 20. Column 20 is provided with reboiler 54 and overhead condenser 56 and herein the normal pentane is distilled substantially completely from the higher boiling non-normal paraffin hydrocarbons in the lean effluent. The normal pentane vapor is passed through line 58 into displacement exchange recycle manifold 60. A portion of the normal pentane is returned as shown as reflux to the column. Line 62 is provided with valve 64 through which net products of pentanes may be taken including any traces of iso and normal pentane which may be present in the feed stream at a flow rate equivalent to that of the entering feed. This prevents isopentane from building up in the displacement exchange recycle stream to an equilibrium value which would be sufficiently high to inhibit effective displacement exchange of normal paraffins of the feed stream by the normal pentane displacement exchange stream.

The normal pentane-free non-normal paraffins of the feed stream are produced through line 66 at a rate controlled by valve 68 from the bottom of lean effluent column 20. This material is cooled in aftercooler 70 and sent to production or further processing facilities not shown through line 72.

In second stage 12 the adsorbent, saturated with normal paraffin hydrocarbons of the feed stream and containing some residual non-normal paraffin hydrocarbons of the feed, is being contacted with a minor portion of the displacement exchange stream to produce the intercut. This material flows from displacement exchange recycle manifold 60 through line 74 and inlet valve 24 through second adsorption zone 12. The produced intercut, containing the residual non-normal hydrocarbons displaced from the adsorbent and some exchange pentane, is discharged through line 76 and outlet valve 32 through line 78 into intercut recycle manifold 80.

The intercut so produced is returned by means of blower 82 at a rate controlled by valve 84 through intercut heater 86 if necessary to maintain the intercut in

the vapor phase. As indicated previously, the intercut constitutes the feed stream to the fourth adsorption stage in this process.

In third contacting zone 14 the adsorbent is being contacted with the major proportion of the displacement exchange stream. This material flows from manifold 60 through line 88 and inlet valve 26 into and through contacting zone 14. Here substantially all the adsorbed normal paraffin hydrocarbons adsorbed from the feed in stage one are preferentially displaced from the adsorbent in exchange for the normal pentane displacement exchange stream. This produces a rich effluent stream comprising the displaced normal paraffins together with some normal pentane. This material flows through outlet valve 34 into extract manifold 90. Manifold 90 opens into rich effluent distillation column 18 provided with overhead condenser 92 and reboiler 94. Here the normal pentane is separated as overhead product from the heavier normal paraffins derived from the feed stream. The overhead pentane vapor is discharged into displacement exchange recycle manifold 60 through which it is recirculated into the appropriate contacting zone by means of blower 96 at a rate controlled by valve 98. Reheater 100 is provided to raise the pentane vapor displacement stream from its distillation temperature to the contacting temperature of about 440° F. and also to overcome heat losses in the system.

The adsorbed normal paraffins, now free of normal pentane displacement exchange material, are removed from the bottom of distillation column 18 at a rate controlled by valve 102 and passed through aftercooler 104 through line 106 to further processing or storage facilities not shown.

In fourth contacting zone 16, the lean adsorbent is contacted with the intercut stream flowing from manifold 80 and line 81 through inlet valve 28. In zone 16 the small quantities of adsorbable normal paraffin constituents present are adsorbed displacing an equivalent amount of normal pentane into admixture with the unadsorbable non-normal paraffin hydrocarbons. This effluent contains the same constituents as the lean effluent from the first adsorption stage 10. It is therefore passed from outlet valve 36 via lines 83 and 52 into the lean effluent column 20 where the normal pentane exchange component is recovered from both streams.

In this process the composition and physical characteristics of the non-normal paraffin lean product stream and of the normal paraffin rich product stream are given below in Tables 2 and 3 respectively:

Table 2

¹ Blending number in iso-octane, 50/50 blend.

It should be understood that each of the four contacting zones shown in Figure 1 and described in the foregoing description is operating in a staggered sequence in which each goes through the four contacting stages described, but 90° out of phase with the others so that the feed stream may be processed continuously and the lean and rich product streams may also be produced continuously.

Referring now more particularly to Figure 2, the process as above described is illustrated in a schematic flow diagram form utilizing a recirculating stream of the granular adsorbent passed downwardly through contact-

ing column 110. The contacting zone is provided at successively lower levels with sealing zone 112, lean effluent disengaging zone 114, adsorption zone 116, feed engaging zone 118, second sealing zone 120, intercut disengaging zone 122, intercut displacement zone 124, first displacement exchange engaging zone 126, third sealing zone 128, rich effluent disengaging zone 130, second displacement exchange zone 132, second displacement fluid engaging zone 134, fourth sealing zone 136, second lean effluent disengaging zone 138, intercut adsorption zone 140, intercut engaging zone 142, and fifth sealing zone 144.

The granular solid adsorbent passes downwardly in succession through these contacting zones in the form of a compact moving bed. The adsorbent is removed from the bottom of contacting column 110 and recirculated through conveyor 146 to the top of the column for re-passage therethrough. In general the fluid pressure existing in contacting column 110 increases at successively lower levels in the column. For purposes of close control it is preferred therefore to employ a conveyor of the type which has a pressure drop from bottom to top and therefore the pneumatic gas lift type solids conveyors in which the solids move as a dilute dispersion in a fluid, or the dense phase conveyors in which the granular solids move upwardly as a dense packed mass at substantially the same density as the downwardly moving bed may be used. In either case the solids conveying force is generated by a fluid flow. Both of these types of conveyors are now well known in the art of solids conveyance.

In order to prevent fluid contamination between the top and the bottom of the column by reason of the fact that fluid flow through the conveyor can occur, lines 148 and 150 are provided controlled respectively by valves 152 and 153 at the top and bottom of the column for the introduction of a seal fluid. These same lines may be employed if desired for the removal of a seal fluid comprising a mixture of the conveyance fluid introduced into the conveyor through line 154 controlled by valve 156 and removed at the top of the conveyor through line 158.

For purposes of illustration the moving bed processes of Figure 2 will be described in connection with the selective adsorption of aromatic hydrocarbons contained in a catalytically reformed C_7 to C_9 hydrocarbon gasoline stream. The zeolitic metallo alumino silicate adsorbent is one having pores of about 13 Å. in diameter and which, because of its preferential adsorption characteristics, preferentially adsorbs the aromatic hydrocarbons leaving the paraffinic, naphthenic, and iso-paraffinic hydrocarbons substantially unadsorbed. The composition of the adsorbent is detailed below.

The feed stream is introduced in the vapor phase at a temperature of about 440° F. through line 160 at a rate controlled by valve 162. This material passes upwardly countercurrent to the descending adsorbent through adsorption zone 116. The displacement exchange stream comprises benzene and accordingly the adsorbent in zone 116 is saturated therewith. The C_7 through C_9 aromatic hydrocarbons are adsorbed on the adsorbent and the non-aromatic C_7 through C_9 hydrocarbons remain unadsorbed and become admixed with the displacement benzene forming the lean effluent stream. This effluent is removed from disengaging zone 114 through line 164 and is introduced together with the product taken from intercut adsorption zone 140 into lean effluent column 166. This column is provided with overhead condenser 168 and bottoms reboiler 170. The lower-boiling benzene displacement exchange material is removed overhead and recirculated through displacement exchange recycle manifold 172. The nonaromatic hydrocarbons boiling above benzene are removed through line 174 at a rate controlled by valve 176 as the lean or non-aromatic hydrocarbon product.

The rich adsorbent flows from the bottom of adsorption zone 116 downwardly into first displacement exchange zone 124. A relatively minor proportion of the displacement exchange stream is passed by means of blower 178 at a rate controlled by valve 180 through heater 182 to raise the benzene vapor from its distillation temperature to the contacting temperature. The vapor flows upwardly countercurrent to the adsorbent thereby displacing residual feed components from the adsorbent together with a minor proportion of the adsorbed aromatic hydrocarbons. This intercut effluent together with recycle benzene is removed from zone 124 and passed through line 184 by means of recycle blower 186 into intercut adsorption zone 140 subsequently described.

The thus treated adsorbent then continues downwardly into second displacement exchange zone 132. The remaining and major proportion of the recycle benzene is passed from manifold 172 by means of blower 188 at a rate controlled by valve 190 through heater 192 which raises the vapor from the distillation temperature to the contacting temperature. The vapor continues upwardly countercurrent to the rich adsorbent in zone 132. Here benzene vapor is adsorbed on the adsorbent in exchange for the adsorbed aromatic hydrocarbons which are displaced producing an aromatic hydrocarbon or rich effluent containing part of the recycled benzene. This effluent flows through line 194 into rich effluent column 196 provided with overhead condenser 198 and bottoms reboiler 200. The displacement exchange benzene is distilled overhead from the heavier aromatic hydrocarbons and introduced into recycle manifold 172 through line 202 at a rate controlled by valve 204. The aromatic hydrocarbons free of benzene are produced as the rich process product through line 206 controlled by valve 208 from the bottom of extract column 196.

As previously indicated, the intercut is introduced by means of blower 186 through a trimmer heater 187 to make up heat losses into adsorption zone 140 in which it is treated countercurrently to the benzene-saturated adsorbent discharged from second displacement exchange zone 132. Here the intercut is treated to adsorb the traces of residual heavier aromatic hydrocarbons in exchange for the adsorbed benzene. The residual non-adsorbable feed components of the intercut and the displaced benzene, constituting the intercut adsorption zone effluent, flow together through line 210 at a rate controlled by valve 212 into admixture with the lean effluent from adsorption zone 116. This material is as stated fractionated in lean effluent still 166 for separation of the displacement exchange benzene and the nonaromatic feed hydrocarbons. Line 167 controlled by valve 169 is provided to bleed out any nonadsorbable hydrocarbons boiling below the C_7 hydrocarbons which may appear in the feed in trace amounts.

In order to avoid intermixing of the fluids in the first, second, third, and fourth contacting zones 116, 124, 142, and 140 respectively, a differential pressure controller instrument is provided connected between each of zones 118—122, 126—130, and 134—138 and respectively actuating a valve in the line opening from the disengaging zone associated with each of the three pairs of adjacent zones. A zero pressure differential is thus maintained by these controllers across each pair of zones to minimize interflow. A typical connection of this type is illustrated at zones 118—122 and involves controller 123 and valve 125 in the outlet line 184.

The composition of the lean nonaromatic and rich aromatic products produced indicates that a substantially complete separation of the aromatic hydrocarbons from the nonaromatic hydrocarbons present in the feed is obtained. The acid solubility, for example, of the extract is 100% whereas the acid solubility of the raffinate is customarily less than 0.5% indicating that a substantially complete separation at near 100% efficiency of the aromatic hydrocarbons results.

The relative quantities or flow rates of the displacement exchange fluid in the second or intercut displacement zone and the third or rich effluent displacement zone vary somewhat depending upon the nature of the adsorbed materials, the nature of the exchange fluid, and the quantity of feed fluid held up in the adsorbent after feed contact. In general however between about 1% and about 10% by volume of the total flow of exchange fluid is used in displacement of the intercut and the remaining 90% to 99% is used in the subsequent displacement of the rich effluent. In most cases however these relative flows are between about 2.5% and about 7.5% and between about 97.5% and about 92.5% respectively.

In the static adsorbent bed modification, this means that after the minor portion of exchange fluid has been introduced into the adsorber and the intercut collected, the outlet is shifted to collect the rich effluent which follows as the major portion flows in.

In the moving adsorbent modification, the relative flow rates of exchange fluid into the second and third contact stages or zones are controlled to maintain these same proportions.

Referring now more particularly to Figure 3, a simplified elevation view of a modification of the contacting zones shown in Figure 1 is illustrated in which a static bed of granular adsorbent is employed. Adsorption vessel 220 is provided at its upper end with fluid inlet 222 and at its lower end with outlet 224. A static bed of adsorbent 226 is indicated schematically within the vessel. As illustrated, the diameter of the vessel and accordingly its cross sectional area open to flow decreases in the flow direction. The extent of this decrease may vary depending upon the circumstances, but preferably it is sufficient to impart to the unadsorbed phase passing through the adsorption zone an increase in velocity of at least 50% and preferably between about 150% and 500% of the velocity. In other words, in this process where exchange displacement takes place, the cross sectional area open to fluid flow through the adsorption vessel shall decrease at least about 33% and preferably between about 60% and about 83% from the open area at the fluid inlet in order to effect this desired increase in fluid velocity. In this way it has been found that the usual adverse effect upon adsorption rate of decreasing concentration of the adsorbable constituents in the fluid contacting the adsorbent may be largely overcome and substantial decreases in the size of the adsorber and in the quantity of adsorbent necessary in each adsorption zone are realized.

It is intended that the apparatus shown in Figure 3 and described above be substituted for any or all of the various adsorption zones 10, 12, 14, and 16 illustrated in Figure 1.

Referring now more particularly to Figure 4, a fragmentary view of a modification of the moving bed adsorption column 110 of Figure 2 is shown in which the cross sectional area open to fluid flow increases with distance from the solids inlet in any given contacting zone. This is provided in adsorption vessel 228 having upper solids inlet 230, lower solids outlet 232, a lower fluid inlet 234 and an upper fluid outlet 236 to permit countercurrent solids fluid contact. If desired, the tapered portion 238 of vessel 228 may be provided with an upper cylindrical portion 240 in which relatively high velocities are maintained for a period after the velocity increase. The flow rate through the vessel in relation to the transverse area open to flow may not be increased above a certain maximum value or else the downward movement of solids is impeded by the pressure gradient developed by the flow, but the relative velocity changes described above may still be effected.

The foregoing descriptions illustrate the application of the present invention to the processing of two industrially representative streams of complex fluid mixtures. It is to be understood that this is not intended to be re-

strictive since the invention is applicable to other complex mixtures in which adsorptive fraction according to molecular species is desired. The process and its intercut production and readorption steps may be applied to other processes using other adsorbents having affinities for particular components of a given mixture.

As an illustration of the improvement in the purity of products produced due to the intercut displacement and readorption steps according to this invention, the following data are given:

A C₆ and C₇ cut from a reformed naphtha treated by a platinum reforming catalyst had the following properties:

Table 4

Boiling range, ° F.	120-218
n-Paraffins, vol. percent	26.6
Gravity, ° API	71.2
Knock rating, F-1+3 ml. TEL	87.4

This material was treated in the vapor phase at atmospheric temperature with a bed of the 5 A. zeolitic metalloc alumino silicate adsorbent discussed above at a temperature of 300° F., the exchange component was normal pentane vapor at the same temperature, no intercut displacement or readorption was used, and the lean non-normal paraffin hydrocarbon effluent and the rich normal paraffin hydrocarbon effluent had the properties given respectively in Tables 5 and 6.

Table 5

Boiling range, ° F.	120-218

The substantial improvement in product purity is apparent from these data, and specifically the normal paraffin contamination is lowered from 4% to below 1.0% in the lean non-normal paraffin effluent while the concentration of normal paraffins in the rich normal paraffin effluent has been raised from 80% to 97% by volume.

The adsorbent employed in the process of this invention is a solid granular material having a mesh size range between about 2 and 200 mesh. It is used in the form of a dense compact bed of material, preferably between about 4 and about 30 mesh, through which the feed and displacement exchange recycle streams pass, either in the vapor phase or in the liquid phase. The process may employ the adsorbent in the form of a single static bed of material in which case the process is only semicontin-

uous. Preferably two or more static beds of adsorbent are employed with appropriate remotely operable valving so that the feed stream is passed through one or more of the adsorbents in a set while the exchange displacement stream passes through one or more of the other adsorbents in the set. In this case, the feed and product flows are continuous, in either the vapor or liquid phase, and either up or down through the adsorbent. The more physically rugged types of granular adsorbent permit the use of the moving solids bed modification in which flow of feed is maintained continuously through an adsorption zone, the flow of displacement exchange fluid is maintained continuously through a desorption zone, and the granular adsorbent is recirculated successively through these two zones. With the smaller sized mesh ranges of adsorbent, such as from about 30 to 300 mesh, the material may be fluidized in and by the fluid streams contacting it, although the compact bed modifications are preferred since a greater number of theoretical and actual contact stages are more readily obtained in smaller and simpler equipment.

Although the present invention may be carried out with most all of the commonly available solid granular adsorbents, particular adsorbents lend themselves to processing particular feedstocks depending upon the specific separation which is to be made. For example, in the separation of aromatic hydrocarbons from coal oil or petroleum hydrocarbon fractions, an adsorbent which preferentially adsorbs the aromatic hydrocarbons should be used. Adsorbents such as silica gel, certain of the preferred adsorbents, and other polar adsorbents are effective in this service. In the treatment of gasoline streams to remove straight chain, low antiknock rating components, an adsorbent which is highly efficient and preferred in this application of the present invention are the natural or synthetic crystalline partially dehydrated metallo alumino silicates. The composition of one typical synthetic zeolite having a pore size of about 4 Å. is $[\text{Na}_2\text{O} \cdot \text{Al}_2\text{O}_3 \cdot (\text{SiO}_2)]$. It may be prepared by heating stoichiometric quantities of alumina and silica and excess caustic under pressure. The excess is washed out and the desired metal ion may then be introduced by ion exchange. Part of the sodium in this material can be ion exchanged with concentrated salt solutions at super-atmospheric pressure and temperatures of 150-300° C. to introduce other metal ions such as calcium to produce

having a pore size of about 5 Å. Certain naturally occurring minerals such as chabazite, analcite, gmelinite, and the like, can be heated to dehydrate the molecule and obtain an activated zeolitic adsorbent similar in adsorption properties to the manufactured materials.

The foregoing adsorbents are typical of those having pore diameters of 7 Å. and less and these are especially well adapted to the adsorption of paraffin hydrocarbons from complex hydrocarbon mixtures.

Another form of zeolitic metallo alumino silicate has a composition substantially corresponding to

and this has uniform pores of approximately 13 Å. in diameter. Another similar material has a composition corresponding substantially to $5\text{CaO} \cdot 6\text{Al}_2\text{O}_3 \cdot 15\text{SiO}_2$ and it has pore diameters of about 10 Å. These and other zeolitic adsorbents having pore diameters of greater than about 7 Å. are not particularly effective in paraffin hydrocarbon adsorption, but they are also extremely efficient in the adsorptive separation of aromatic hydrocarbons and sulfur compounds from complex hydrocarbon streams containing these materials.

These natural and synthetic materials are all zeolites and their sodium and calcium derivatives are very stable adsorbents which apparently have "pores" available for adsorption which are quite uniform in size. Other de-

rivatives have different sized "pores." These are the preferred adsorbents for use in the process of this invention. The molecules which are the more readily adsorbable and for which the adsorbent, having pores of less than 7 Å., exert preferential adsorptive forces are those having straight chain molecules whose minimum dimensions are equal to or slightly less than these pore dimensions. Thus the normal paraffins and normal olefins with cross chain dimensions of under 5 Å. are very strongly and very readily adsorbed by these below 7 Å. materials. However the branched chain paraffins or olefins, and the naphthene and aromatic hydrocarbons, all having molecular dimensions in the shortest direction in excess of 5 Å. are substantially nonadsorbable. These adsorbents are thus selective for normal paraffins, and normal olefins if present, and will not adsorb any appreciable quantity of other hydrocarbons. Other derivatives of these particular inorganic adsorbent materials have uniformly sized pores greater than about 7 Å. and ranging as high as from 12 to 13 Å. These will adsorb molecules having a dimension less than about 12 Å. such as aromatic hydrocarbons and will exclude a material whose minimum molecular dimension is above 12 Å.

Other adsorbents such as activated charcoal, activated alumina, and other well known materials are applicable herein to particular feed mixtures. However, their specific affinities for particular compounds must be considered in connection with the specific feed mixture in order to determine whether a particular component will be present in the extract phase produced from the adsorbent by the displacement exchange or will be present in the raffinate phase from the adsorber.

Some of these adsorbents, particularly silica gel and activated alumina tend to adsorb rather strongly polar materials to varying degrees. The metallo alumino silicates adsorb polar molecules to a considerably lesser extent. In gasoline treating this interferes with the fractionation of gasoline hydrocarbons as a function of molecular shape. Accordingly it is contemplated in this invention to contact the feed stream first with a material which exhibits very strong adsorptive forces for these polar materials and remove them from the stream to be treated. This pre-adsorption or pretreating of the feed may be accomplished by contacting the feed stream with an inorganic halide such as copper chloride, calcium chloride, magnesium chloride, and the like. In this way large and highly polar materials such as ethers, thioethers, water alcohols, mercaptans, and amines are readily removed from the feed. Also removable in this way are the highly polar nitrogen and sulfur compounds which commonly occur in small amounts in gasolines. These specifically include such materials as thiophene and the alkylated thiophenes, pyridine and alkylated pyridines. Thus this pretreatment removes these polar materials and prevents them from interfering with the subsequent fractionation in which the feed is separated into streams containing components of a specific molecular size or structure.

Although the pre-adsorption step prevents rapid deactivation of the main adsorbent beds, some deactivation may eventually occur. It is within the contemplation of this invention to regenerate the adsorbent periodically by high temperature stripping with steam etc. to desorb impurities with hot flue gas, or to burn off the impurities as in catalyst regeneration, or both.

A particular embodiment of the present invention has been hereinabove described in considerable detail by way of illustration. It should be understood that various other modifications and adaptations thereof may be made by those skilled in this particular art without departing from the spirit and scope of this invention as set forth in the appended claims.

We claim:

1. A process for separating fluid mixtures which comprises first contacting the mixture with a solid adsorbent

saturated with a displacement exchange component thereby adsorbing the more readily adsorbable constituents of said mixture and displacing said exchange component into admixture with the less readily adsorbable constituents forming a first lean effluent, separating said exchange component from said lean effluent leaving said less readily adsorbable constituents, next contacting the adsorbent with a minor portion of recirculated exchange component to displace an intercut effluent, then contacting the adsorbent with the remaining portion of said exchange component thereby resaturating said adsorbent with part of said exchange component and displacing said more readily adsorbable constituents from the adsorbent into admixture with the remainder of said exchange component to form a rich effluent, separating said exchange component from said rich effluent leaving said more readily adsorbable constituents, contacting said adsorbent with said intercut effluent to adsorb the more readily adsorbable constituents present therein and displacing into admixture with the less readily adsorbable constituents thereof some of the exchange component as a second lean effluent, combining said second lean effluent with said first lean effluent for separation of said exchange component, and recirculating the exchange component recovered from the combined lean effluents and from said rich effluent in the process.

2. A process according to claim 1 wherein said displacement exchange component has a boiling point different from that of most of the constituents of said said fluid mixture, and wherein it is separated from said lean and rich effluents by distillation.

3. A process according to claim 1 in combination with the steps of controlling the flow of exchange component so that said minor and major portions thereof are between about 1% and about 10%, and between about 99% and about 90%, by volume, respectively.

4. A process according to claim 1 wherein the adsorbent is contacted with said feed mixture, the minor and major portions of exchange component, and said intercut effluent in sequence at substantially the same temperatures.

5. A process according to claim 1 wherein a plurality of static beds of said adsorbent is contacted in a staggered sequence with said fluid mixture, said exchange stream, and said intercut to produce substantially continuous streams of the less readily adsorbable and more readily adsorbable constituents as process products.

6. A process according to claim 1 wherein said adsorbent is recirculated in a stream successively through a feed mixture contacting zone, an intercut displacement zone, a displacement exchange zone, and an intercut adsorption zone in a contacting column.

7. A process according to claim 1 in combination with the step of increasing the velocity of fluid flow in the flow direction during contact of at least one of said fluids with said solid adsorbent.

8. A process according to claim 1 wherein said fluid mixture comprises a hydrocarbon mixture.

9. A process for the separation of fluid hydrocarbon mixtures which comprises contacting the feed mixture with a lean adsorbent saturated with an exchange hydrocarbon boiling apart from said mixture thereby adsorbing the more readily adsorbable hydrocarbons and displacing said exchange hydrocarbon into admixture with the less readily adsorbable hydrocarbons of said mixture as a first lean effluent, then contacting the adsorbent with a minor portion of recycled exchange hydrocarbon to displace an intercut effluent therefrom, next contacting the adsorbent with a major portion of recycled exchange hydrocarbon thereby resaturating said adsorbent with one part and displacing said more readily adsorbable hydrocarbons into admixture with the other part of said major portion to form a rich effluent, finally contacting the adsorbent with said intercut effluent to adsorb traces of said more readily adsorbable hydrocarbons to form

a second lean effluent, combining said first and second lean effluents, distilling said exchange hydrocarbon therefrom, distilling said exchange hydrocarbon from said rich effluent, recirculating the thus recovered exchange hydrocarbon in the process, controlling the relative volumes of said minor and major portions of said exchange hydrocarbon to between 1% and 10% and between 99% and 90% by volume respectively and thereby effecting efficient adsorptive separation of said less readily and more readily adsorbable hydrocarbons from one another without the usual cyclic heating and cooling of said adsorbent.

10. A process according to claim 9 wherein said adsorbent comprises a zeolitic metallo alumino silicate activated by partial dehydration and having substantially uniform diameter pores of 7 Å. and less, and said more readily adsorbable hydrocarbons comprise normal paraffins.

11. A process according to claim 10 wherein said zeolitic metallo alumino silicate has a composition corresponding substantially to $[\text{CaO} \cdot \text{Al}_2\text{O}_3 \cdot (\text{SiO}_2)_2]_{0.7}$ $[\text{Na}_2\text{O} \cdot \text{Al}_2\text{O}_3 \cdot (\text{SiO}_2)_2]_{0.3}$ and has substantially uniform diameter pores of about 5 Å.

12. A process according to claim 9 wherein said adsorbent comprises a zeolitic metallo alumino silicate activated by partial dehydration and having substantially uniform diameter pores in excess of 7 Å. and said more readily adsorbable hydrocarbons comprise aromatic hydrocarbons.

13. A process according to claim 12 wherein said zeolitic metallo alumino silicate has a composition corresponding substantially to $5\text{Na}_2\text{O} \cdot 6\text{Al}_2\text{O}_3 \cdot 15\text{SiO}_2$ and has substantially uniform pore diameters of about 13 Å.

14. A process according to claim 9 in combination with the steps of maintaining an adsorption zone, an intercut displacement zone, a displacement exchange zone, and an intercut adsorption zone, passing said adsorbent as a moving bed downwardly by gravity through said zones in succession, and recirculating said adsorbent from the lowermost to the uppermost zone for repassage therethrough.

15. A process according to claim 9 in combination with the steps of maintaining an adsorption zone, a first sealing section, an intercut displacement zone, a second sealing section, a displacement exchange zone, a third sealing section and an intercut adsorption zone; passing said adsorbent in a moving bed downwardly by gravity through each of said zones in succession; and controlling the flow of fluid from one zone to another so as to maintain a pressure differential substantially equal to zero across each of said sealing sections.

16. A process according to claim 9 in combination with the step of adjusting the temperature of said exchange hydrocarbon distilled from said lean and rich effluents to a value substantially equal to that at which said feed mixture contacts said adsorbent whereby said more readily adsorbable hydrocarbons are recovered through displacement exchange from said adsorbent at substantially the same temperature at which they were adsorbed thereby from said feed mixture.

17. In a process for the adsorptive fractionation of a fluid mixture of constituents of different degrees of adsorbability which comprises contacting a solid adsorbent with the fluid mixture to adsorb part thereof leaving an unadsorbed lean effluent and then desorbing the adsorbed part by contact with a desorption fluid to form a rich effluent and leaves lean adsorbent, the improvement which comprises collecting an intercut effluent produced during the flow of not more than the first 10% by volume of the desorption fluid separately from the rich effluent produced during the flow of at least the subsequent 90% of said fluid, then contacting said adsorbent with said intercut effluent to produce a second lean effluent, and combining said second lean effluent with said

15

unadsorbed lean effluent whereby intercontamination between the lean and rich effluents is substantially reduced.

18. A process according to claim 17 wherein the fluid mixture and said desorption fluid contact said adsorbent separately at substantially the same temperature, in combination with the steps of separating said desorption fluid from said lean and rich effluents and recirculating it as a displacement exchange fluid into contact with said ad-

16

sorbent to produce in order said intercut effluent and said rich effluent and to saturate said lean adsorbent therewith.
